UNITED STATES PATENT OFFICE.

ROBERT S. HICKISH, OF TUCKAHOE, NEW YORK, ASSIGNOR OF ONE-HALF TO EDWARD M. BENFORD, ONE-FOURTH TO DAVID BENFORD, AND ONE-FOURTH TO SARAH BENFORD, ALL OF MOUNT VERNON, NEW YORK.

GREASE-GUN.

1,139,865.

Specification of Letters Patent. Patented May 18, 1915.

Application filed February 6, 1914. Serial No. 816,872.

To all whom it may concern:

Be it known that I, ROBERT S. HICKISH, a subject of the King of Hungary, residing at Tuckahoe, in the county of Westchester and State of New York, have invented certain new and useful Improvements in Grease-Guns, of which the following is a specification.

This invention relates to grease guns, the object of the invention being to provide a simple, inexpensive and effective grease gun which may be used either for oil or heavy grease as occasion may require and in which the operation of the piston will be facilitated, and in which also the piston may be readily locked, held or retained against manipulation in one way by a very simple device, which locking or holding means will also assist in reducing friction.

In the drawings accompanying and forming part of this specification, Figure 1 is an exterior view of this improved grease gun; Fig. 2 is a partly sectional view thereof; Figs. 3 and 4 are detail enlarged views illustrating the position of the holding device at different times; and Figs. 5 and 6 are cross-sectional views illustrating respectively the position of the holding device shown in Figs. 4 and 3.

Similar characters of reference indicate corresponding parts throughout the several figures of the drawings.

This improved grease gun comprises the usual cylinder 2 having a removable cap 3, the removal of which will permit the heavy grease to be inserted. This cap is provided with any desired form of nozzle 4.

Within the gun is located some suitable form of piston 5 connected to a plunger or piston rod 6 which is threaded as at 7, and provided with a handle as at 8 by means of which the plunger may be either reciprocated, that is, moved or slid back and forth or rotated. Carried by the rear of the cylinder or that end opposite from the nozzle is a removable closure or cap 9 having a tubular extension 10 provided with an opening 11 therein in which is located a ball 12 which co-operates with the thread of the plunger. This ball is maintained in its opening or pocket 11 by means of a rotatable housing or collar 12' located on the extension 10 of the cap. The rotatable movement of this housing or collar is limited by means of a

pin 13 carried by the extension 10, the pin 55 projecting into a recessed portion 14 of the collar. The collar is also provided with an opening 12", which on the rotation of the collar, can be made to register with the opening or pocket 11 in the extension, a pin 60 15 extending across the opening in the collar to prevent the ball from falling out. The thread of the plunger is formed as a quick worm, for instance three threads to the inch.

In the present improvement when it is desired to slide the plunger as with ordinary fluid grease, such as oil, it is merely necessary to turn the knurled collar so that the opening therein will register with the opening in the extension, whereupon the ball will have sufficient play to permit the plunger to be reciprocated or slid back and forth, the opening in the collar permitting this play of the ball. When, however, it is desired to use the gun with heavy grease difficult to push out by merely pushing upon the plunger, it is necessary that the piston be rotated by means of the screw and for this purpose the collar is simply turned so as to carry the opening thereof away from the ball, whereupon the ball is locked or held as it were in the grooves of the threads so that it is only possible to operate the piston by rotating the plunger while the ball at the same time also constitutes an anti-friction bearing to reduce friction during this operation. It will thus be observed that by means of this holding device the piston can be locked or unlocked at any position throughout its entire length as occasion may require.

I claim as my invention:

1. A grease gun comprising a cylinder having a piston therein and a threaded sliding and rotatable piston rod therefor, and means for holding said piston against sliding movement, said means including a ball and a rotatable holding member.

2. A grease gun comprising a cylinder having a piston therein and a threaded sliding and rotatable piston rod therefor, and means for holding said piston against sliding movement, said means including a ball and a knurled rotatable holding member.

3. A grease gun comprising a cylinder, having an extension provided with an opening, and a piston, a threaded sliding and ro-

5. A rotatable piston rod therefor, and means for holding said piston against sliding movement, said means comprising a rotatable member located on said extension and having an opening therein and a ball located in the opening of said extension. 50
4. A grease gun comprising a cylinder, having an extension provided with an opening, and a piston, a threaded sliding and rotatable piston rod therefor, and means for holding said piston against sliding movement, said means comprising a rotatable member located on said extension and having an opening therein, a ball located in the opening of said extension, and means for maintaining the ball in place when said openings register, and means for limiting rotary movement of said member and comprising a pin carried by the extension and a recess 55 carried by said rotatable member.
10. A grease gun comprising a cylinder, having an extension provided with an opening, and a piston, a threaded sliding and rotatable piston rod therefor, and means for holding said piston against sliding movement, said means comprising a rotatable member located on said extension and having an opening therein, a ball located in the opening of said extension, and means for maintaining the ball in place when said openings register. 60
15. A grease gun comprising a cylinder, having an extension provided with an opening, and a piston, a threaded sliding and rotatable piston rod therefor, and means for holding said piston against sliding movement, said means comprising a rotatable member located on said extension and having an opening therein, a ball located in the opening of said extension, and means for maintaining the ball in place when said openings register, and means for limiting rotary movement of said member. 65
20. A grease gun comprising a cylinder, having an extension provided with an opening, and a piston, a threaded sliding and rotatable piston rod therefor, and means for holding said piston against sliding movement, said means comprising a rotatable member located on said extension and having an opening therein, a ball located in the opening of said extension, and means for maintaining the ball in place when said openings register, said last means comprising a pin extending across the opening of said member. 70
25. A grease gun comprising a cylinder, having an extension provided with an opening, and a piston, a threaded sliding and rotatable piston rod therefor, and means for holding said piston against sliding movement, said means comprising a rotatable member located on said extension and having an opening therein, a ball located in the opening of said extension, and means for maintaining the ball in place when said openings register, and means for limiting rotary movement of said member. 75
30. A grease gun comprising a cylinder, having an extension provided with an opening, and a piston, a threaded sliding and rotatable piston rod therefor, and means for holding said piston against sliding movement, said means comprising a rotatable member located on said extension and having an opening therein, a ball located in the opening of said extension, and means for maintaining the ball in place when said openings register, and means for limiting rotary movement of said member. 80
35. A grease gun comprising a cylinder, having an extension provided with an opening, and a piston, a threaded sliding and rotatable piston rod therefor, and means for holding said piston against sliding movement, said means comprising a rotatable member located on said extension and having an opening therein, a ball located in the opening of said extension, and means for maintaining the ball in place when said openings register, and means for limiting rotary movement of said member. 85
40. A grease gun comprising a cylinder, having an extension provided with an opening, and a piston, a threaded sliding and rotatable piston rod therefor, and means for holding said piston against sliding movement, said means comprising a rotatable member located on said extension and having an opening therein, a ball located in the opening of said extension, and means for maintaining the ball in place when said openings register, and means for limiting rotary movement of said member.
45. A grease gun comprising a cylinder, having an extension provided with an opening, and a piston, a threaded sliding and rotatable piston rod therefor, and means for holding said piston against sliding movement, said means comprising a rotatable member located on said extension and having an opening therein, a ball located in the opening of said extension, and means for maintaining the ball in place when said openings register, and means for limiting rotary movement of said member.
